(57) **CLAIM**

The ornamental design for a display panel or screen with graphical user interface, as shown and described.

DESCRIPTION

FIG. 1 is a front elevational view of a display panel or screen with graphical user interface showing a first image; and, FIG. 2 is a front elevational view of a second image thereof. The appearance of the image transitions sequentially between or among the images shown in FIGS. 1-2. The process or period in which an image transitions to another forms no part of the claimed design.

The broken line showing of a display panel or screen, and other elements forms no part of the claimed design.
